APPARATUS FOR COMPENSATING HYGROSCOPIC EXPANSION OF PAPER IN PRINTING PRESSES

Theodore Makarius, Flushing, and James Verzera, Jackson Heights, Long Island, N. Y., assignors to Olsen Mark Corporation, New York, N. Y., a corporation of New York

Application July 27, 1939, Serial No. 286,850

6 Claims. (CL 271—48)

This invention relates to the printing art and more particularly refers to improvements in multi-color printing processes and in printing presses used in connection therewith.

6 In multi-color printing it is of the utmost importance to insure exact juxtaposition of successive impressions if the result is to be a color composition in which the colors blend harmoniously with one another without any evidence of offset printing.

The necessity of thus producing perfect work calls for a great deal of skill on the part of the printer, who must be expert in arranging the printing plates on the various impression cylinders, as well as the paper guides and other elements controlling the travel of the paper sheets through the press, in order to coordinate their functions in perfect timing and perfect register.

One of the difficulties with which the printer has to contend is the tendency of paper to absorb moisture which frequently causes the length and breadth of the paper sheets to vary from one impression to another. For instance, it frequently happens that a paper sheet which has been subjected to a first impression may be found to be somewhat longer and wider when it is passed to the next impression, especially, if between impressions the sheet has had a chance to absorb moisture from the surrounding air and to have become impregnated with the ink of the first impression.

It follows, that if some compensation, counterbalancing such variations of size, is not provided, the various impressions will fail to be in exact register and the result will be an inferior or totally defective composition.

Such increases as may occur in the length of the sheet, that is, in the direction of the press feed, may be compensated with comparative ease by adjusting the distance of the printing plates from the center of the printing cylinder upon which they are mounted by such minute quantities as may be sufficient to cause changes in the circumferential extension of the printing surface as will correspond to the variations as may have taken place in the length of the sheets. To this end, adequate provisions for adjustment are usually provided in printing presses of standard design and no particular problem in insuring exact register of the various impressions may be said to exist.

The variations which take place in the breadth of the sheets, however, constitute a real problem for the printer because to our knowledge no adequate provisions for compensating adjustment

have been heretofore provided. In order to meet these conditions skilled operators will at times resort to some makeshift expedient which may improve the register of the successive impressions to a certain extent, but which are always uncertain in their operation and may not be depended upon to insure uniformly good results.

Furthermore, such makeshift arrangements as the printer may resort to usually consume a great deal of time and since they generally require a number of printing tests they also result in a material wastage of paper. When the paper is very hygroscopic or when the air is highly charged with moisture, the expansion of the paper may be such that its adequate compensation will be very difficult, if not impossible, to achieve. Under abnormal conditions of humidity, a paper sheet originally about four feet wide may expand as much as a quarter of an inch or more and an expansion of one-eighth of an inch is not at all uncommon.

The primary object of this invention is to provide, in a printing press, a novel and improved device for compensating the hygroscopic expansion taking place in the paper sheets transversely to the direction of the press feed, whereby said sheet may be "drawn in" more or less substantially so as to restore the original distance between its side edges and insure correct register of successive impressions.

A further object is to provide, in a printing press, a device of the character specified, of a simple and effective design, said device being easily mounted on a standard press and being controllable from a distance without interference with the normal operation of the press.

Other objects and advantages of the present invention will more fully appear as the description proceeds and will be set forth and claimed in the appended claims.

Our invention is illustrated by way of example in the accompanying drawings, in which:

Fig. 1 is a plan view of a conventional delivery platform between two impression cylinders in a printing press, equipped with a device embodying our invention;

Fig. 2 is a vertical longitudinal section thereof;

Fig. 3 is a front end view of the same;

Fig. 4 is a plan view of the front unit of our device for compensating the hygroscopic expansion occurring at the front end of the sheet;

Fig. 5 is a side view in elevation thereof;

Fig. 6 is a vertical longitudinal section of the same, in an enlarged scale, taken through line 6—6 of Fig. 4;

Fig. 7 is a plan view of the rear unit of our

device for compensating the hygroscopic expansion taking place at the rear end of the sheet;

Fig. 8 is a vertical longitudinal section thereof; and

5 Fig. 9 is a side view in elevation thereof.

Referring to Figs. 1 to 3, 10 designates an impression cylinder in a multi-color printing press, 11 designates another impression cylinder for the next color impression and 12 generally designates 10 the delivery platform between the two cylinders, the sheet discharged from cylinder 10 being delivered to said platform to be fed to the grippers (not shown) serving the next impression cylinder.

The actual delivery to the grippers is effected 15 by a plurality of longitudinally directed endless feed tapes 13, 14, 15, 16, riding over end pulleys 17, 18, the operation of said feed tapes being intermittent and being timed with the operation of the impression cylinders.

20 The delivery platform usually also comprises a number of longitudinally directed bars 19, 20, located between adjoining feed tapes, and a plurality of front end supports 21, adjustably clamped onto a transversely directed round bar 25 22.

As we have previously explained, according to our invention the increase in the width of a sheet due to hygroscopic expansion is compensated by slightly raising the central longitudinal portion 30 of the sheet above the level of the supporting feed tapes so as to draw in the side edges of the sheet a certain amount, sufficient to restore the original distance between said side edges.

Referring more particularly to Fig. 3, in which 35 23 designates a paper sheet discharged by the first impression cylinder onto the delivery platform, it will be seen that said sheet is raised at 24 along its central longitudinal line by means of a supporting device, the upper surface of which 40 is at a somewhat higher level than that of the feed tapes, so that the paper sheet acquires a slant from the center towards each side.

Due to this arrangement the distance between the side edges 25, 26 of the sheet is naturally 45 somewhat less than if the sheet were allowed to remain in a flat condition, so that by adjusting the height of the central supporting device it is possible to draw in the side edges more or less as conditions may demand.

50 In the preferred form of our invention the supporting element for the central longitudinal portion of the sheet is in the form of a tape 27 extending between a front arm 28 and a rear arm 29, said arms being adjustable in a vertical plane 55 so as to raise more or less the front and rear ends of said tape.

The front arm 28 forms part of what we call 60 the front unit of our device, said front unit being generally designated by the letter A, and rear arm 29 forms part of the rear unit B, which is mounted in a board 30, said board being placed in position on the delivery platform by removing the central longitudinal bar between feed tapes 14, 15, and setting it in its place.

65 As stated, arms 28, 29 may be raised or lowered at will so as to accordingly raise or lower the front and rear ends of the tape 27, and the operation of said arms 28, 29 may be effected from a point external to the press where the control 70 unit C is located.

As Fig. 1 clearly shows, said control unit consists of a bracket or support 31 having two laterally spaced hubs 32, 33, in which are rotatably mounted control knobs 34, 35. Said knobs are 75 connected by a flexible shaft to the operating

mechanism of units A and B, respectively, said flexible shafts being housed within casings of flexible tubing formed by lengths of flexible tubing 36, 37, respectively.

The tape 27 is maintained in a taut condition 5 under a uniform tension exerted by a weight 38, attached to its rear end 39, said rear end of tape 27 being deflected downwardly by an idle pulley 40.

The constructional details of the units forming 10 the device illustrated in Figs. 1 and 2 are shown in greater detail in Figs. 4 to 6 for the front unit and Figs. 7 to 9 for the rear unit.

Referring to Figs. 4 to 6, it will be seen that each front end support 21 is in the form of a 15 clamp adapted to be fixed along round bar 22 by means of a clamping screw 41, said clamp having a tongue-like extension 42 directed towards the next impression cylinder. The front unit is mounted upon the tongue-like extension of the 20 support or clamp 21 located in proximity of the central longitudinal line of the delivery platform. The unit comprises a main body 43 which is formed with a longitudinal opening, the width of which corresponds to the width of extension 25 42, so that main body 43 can be mounted onto the extreme end of extension 42 by inserting said end within said opening and clamping said main body firmly in position by means of two set screws 44, 45.

In said main body 43 is rotatably mounted a transversal shaft 46, carrying at one end a worm wheel 47 and at the other end a finger 48 radially extending therefrom.

At the side of body 43 against which radial 35 finger 48 extends is pivotally mounted at 49 a longitudinally extending lug 50 carrying the frontwardly extending thin narrow plate 28. Pivot 49 is frontwardly spaced with respect to shaft 46 so that lug 50, rearwardly extending 40 from said pivot 49, by virtue of its own weight tends to bear against the outer end of finger 48, as Fig. 6 clearly shows.

The front end of tape 27, which is preferably 45 made of strip steel, is bent to form a hook 52, so adapted to engage the outer end of plate 28, so that if a tension is exerted upon tape 27 and shaft 46 is rotated so as to move finger 48 to a lower position, plate 28 will be tilted upwardly to an inclined position, such as shown at 28' in Fig. 5, 50 to whatever extent is permitted by the quantity by which finger 48 has been lowered.

The operation of worm wheel 47 is effected by means of a worm 53, carried by a flexible shaft 54 housed within a flexible casing 36, said worm 55 being rotatably mounted between two lugs 55, 56, outwardly projecting from the surface of main body 43.

As previously explained, the flexible shaft 54 together with its casing 36 extend to a convenient point of control where the shaft is connected to knob 34.

The rear unit consists of a longitudinal box or casing 57, attached to the underside of board 30, which board has a through opening 58 in correspondence of said box or casing. Said box or casing is formed with a longitudinal chamber 59, within which is housed an arm 29, pivotally mounted at 61, said arm carrying at its extreme end a roller 62 and being provided at its pivoted 70 end with a worm wheel 63, which is permanently fixed to said arm.

Worm wheel 63 is operated by means of a worm 75 64 in mesh therewith, said worm being supported between two bearings 65, 66, and being actuated 75

5 by a flexible shaft 67 housed within flexible casing 37. At the rear end of chamber 59 is rotatably mounted a roller 40, which as previously stated acts as a means for deflecting downwardly the rear end 39 of tape 27.

10 Flexible shaft 67 and its casing 37 extend, as stated, to a suitable remote point of control where shaft 67 is actuated by means of a knob 35 to cause any desired angular displacement of arm 10 29 so as to raise the lower roller 62 any desired amount.

15 Tape 27 the front end of which, as stated, is hooked over the front end of plate 28 extends rearwardly therefrom to roller 62 by which it is also supported and then continues towards deflecting roller 40 by means of which it is deflected 15 downwardly.

20 It is, therefore, obvious that by operating knob 34 so as to lower finger 48 any desired amount, arm 28 will be enabled to respond to the tensional force exerted upon tape 27 by weight 38, so that plate 28 will acquire an upwardly inclined position as shown at 28' in Fig. 5 and the front end of tape 27 will be raised a corresponding amount. 25 Similarly, by proper operation of knob 35 arm 29 may be angularly displaced so as to raise roller 62 and with it the rear end of tape 27 the proper amount required for compensating the hygroscopic expansion of a paper sheet at the rear end 30 thereof.

25 By virtue of the arrangement described it is possible to very gradually adjust the inclination of arms 28, 29, independently of each other, so that the central longitudinal portion of the paper sheet may be raised more at the front than at the rear or vice versa, according to the compensating action required, without disturbing the normal operation of the press. The necessary adjustments can be quickly effected in a positive manner, so as to set the tape 27 in a permanently adjusted position which may be found by testing a few sheets in succession until the correct juxtaposition of the printing impressions has been realized. Once the correct position of the tape 45 27 has been found, normal printing operations may be conducted on the entire run of sheets to be printed with a certainty of obtaining uniform and satisfactory results.

30 The fact that the sheet of paper is presented to the grippers serving the impression cylinder while it is slightly sloping from the center towards the sides and, therefore, not in a perfectly flat condition, would lead one to assume that in passing through the cylinders the sheet might become 35 slightly wrinkled. In practice, however, such is not the case because while the printing operation takes place the sheet is held firmly by the grippers and the width compensation differential between adjoining grippers in the row is so small that 40 neither the printing nor the paper itself are affected by the condition thereby created.

45 For instance, assuming that a sheet originally four feet wide has become one-eighth of an inch wider due to hygroscopic absorption and that the grippers are six inches apart, each section of paper intervening between two grippers would only have been subjected to a fractional expansion of one sixty-fourth of an inch, that is, a negligible quantity so far as the possibility of 50 wrinkling is concerned.

55 The device illustrated and described is extremely simple and may be easily mounted in position in existing printing presses. It is obvious, however, that arrangements other than the 75 one described may be used for adjusting the

amount of vertical displacement of the tape 27, or other equivalent element which may be used for performing the same function.

60 For instance, in the device illustrated the means for raising arm 28 above its normal level is constituted by the weight 38 exerting a pull on tape 27, finger 48 tending to oppose the movement of said arm 28 in an upward direction. It can easily be seen, however, that arm 28 could be positively operated with equal ease by flexible shaft 54, as is done in the case of arm 29.

65 The drawings should, therefore, be understood as being intended for illustrative purposes only and not in a limiting sense.

70 We, accordingly, reserve the right to carry our invention into practice in all those ways and manners which may enter, fairly, into the scope of the appended claims.

We claim:

75 1. In a printing press the combination, with an impression cylinder served by a set of grippers, and longitudinally movable means for delivering a paper sheet to a position where said grippers will grip the front edge thereof, of a longitudinally directed flexible strip adapted to underlie the central longitudinal portion of said sheet, a member adjustable in a vertical plane engaging one end of said strip, another member adjustable in a vertical plane supporting said strip in proximity of its other end, the latter 30 end being deflected downwardly, a weight attached to said latter end maintaining said strip under tension, and means for controlling said adjustable members to more or less raise said strip above the normal level of said longitudinally movable means.

80 2. In a printing press the combination, with an impression cylinder served by a set of grippers, and longitudinally movable means for delivering a paper sheet to a position where said grippers will grip the front edge thereof, of a longitudinally directed flexible strip adapted to underline the central longitudinal portion of said sheet, a pivotally mounted arm movable in a vertical plane, underlying and engaging the front 45 end of said strip, a pivotally mounted arm movable in a vertical plane underlying and supporting said strip at the rear, the rear end of said strip being deflected downwardly, a weight attached to said rear end maintaining said strip under tension, and means controllable from a remote point for controlling said arms to more or less raise said strip above the normal level of 50 said longitudinally movable means.

85 3. In a printing press the combination, with an impression cylinder served by a set of grippers, and longitudinally movable means for delivering a paper sheet to a position where said grippers will grip the front edge thereof, of a 60 longitudinally directed flexible strip adapted to underlie the central longitudinal portion of said sheet, a pivotally mounted arm movable in a vertical plane, underlying and engaging the front end of said strip, a rotatably mounted finger 65 tending to oppose the movement of said arm in an upward direction, a worm wheel in a fixed relation to said finger, a pivotally mounted arm movable in a vertical plane underlying and supporting said strip at the rear, the rear end of 70 said strip being deflected downwardly, a weight attached to said rear end maintaining said strip under tension, a worm wheel in fixed relation to the latter arm, a worm in mesh with each worm wheel, a flexible shaft connected to and 75

extending from each worm, and manually operable means for rotating each shaft.

4. In a printing press the combination, with an impression cylinder served by a set of grippers, and longitudinally movable means for delivering a paper sheet to a position where said grippers will grip the front edge thereof, of a longitudinally directed flexible strip adapted to underlie the central longitudinal portion of said sheet, a member adjustable in a vertical plane engaging one end of said strip, another member adjustable in a vertical plane supporting said strip in proximity of its other end, means for maintaining said strip under tension, and means for controlling said adjustable members to more or less raise said strip above the normal level of said longitudinally movable means.

5. In a printing press the combination, with an impression cylinder served by a set of grippers, and longitudinally movable means for delivering a paper sheet to a position where said grippers will grip the front edge thereof, of a longitudinally directed flexible strip adapted to underlie the central longitudinal portion of said sheet, a pivotally mounted arm movable in a vertical plane, underlying and engaging the front end of said strip, a pivotally mounted arm mov-

able in a vertical plane underlying and supporting said strip at the rear, the rear end of said strip being deflected downwardly, means for maintaining said strip under tension, and means controllable from a remote point for controlling said arms to more or less raise said strip above the normal level of said longitudinally movable means.

6. In a printing press the combination, with an impression cylinder served by a set of grippers, and longitudinally movable means for delivering a paper sheet to a position where said grippers will grip the front edge thereof, of a longitudinally directed flexible strip adapted to underlie the central longitudinally portion of said sheet, a member adjustable in a vertical plane engaging one end of said strip, another member adjustable in a vertical plane supporting said strip in proximity of its other end, means for maintaining said strip under tension, and a flexible shaft controlling each adjustable member independently of the other to more or less raise said strip above the normal level of said longitudinally movable means.
